LIPA POLINKOWSKY, OF LONDON, ENGLAND, ASSIGNOR TO WESTERN ELECTRIC COMPANY, INCORPORATED, OF NEW YORK, N. Y., A CORPORATION OF NEW YORK.

CALL-DISTRIBUTING SYSTEM.

1,299,606.

Specification of Letters Patent.

Patented Apr. 8, 1919.

Application filed March 24, 1917. Serial No. 157,095.

To all whom it may concern:

Be it known that I, LIPA POLINKOWSKY, a subject of the Emperor of Russia, residing at London, England, have invented certain 5 new and useful Improvements in Call-Distributing Systems, of which the following is a full, clear, concise, and exact description.

This invention relates to a call distributing system for telephone exchanges and 10 more particularly to systems in which calls are automatically extended to an operator's position, and, depending upon the busy or idle condition of the connecting apparatus thereat, are associated with such connecting 15 apparatus. It has been heretofore proposed to distribute calls to operators' positions and to prevent the distribution of such calls to an operator's position as long as an operator at such position is engaged. It has also 20 been proposed to distribute calls to operators' positions which are maintained busy for a predetermined period of time, irrespective of whether or not the operator is engaged, so that a subsequent call may be 25 distributed to a position after a definite time interval which is in practice slightly less than the time which the operator under normal conditions utilizes in performing her duties in connection with a call.

30 It is an object of the present invention to obtain the advantages of both of the schemes outlined above, that is, to provide for the distribution of calls to a position at definite and predetermined intervals, which intervals, however, may be automatically varied 35 in case, due to some unusual condition arising at the operator's position, the operator has not disposed of a preceding call within the usual time. Therefore, in accordance 40 with a feature of the invention, means are provided so that after a call is extended to an operator's position, means is made operative to prevent the distribution of another call to that position for a predetermined 45 time interval which may be slightly less than the time interval utilized by an operator in extending a call, and also provision of further means which is brought into operation in case the time consumed by the operator in extending the call is longer than the 50 normal interval, which will modify the first-mentioned means so that the operator's position is maintained busy to subsequent calls for a longer time interval than normal. For 55 example, if a call is extended to the opera-

tor's position, timing means is brought into operation to maintain the position busy for a predetermined time interval. When a second call comes in, if the first call is being attended to at the operator's position in a 60 normal manner, such second call may be distributed to the position after a predetermined time interval. On the other hand, if the first call is not attended to in the normal manner, the operation of the timing is modified so that a longer predetermined time interval will elapse before the second call can be associated with the operator's active apparatus. Furthermore, if, after the elapse 65 of this longer interval still another call is 70 extended to the operator's position, and if not only one but two calls are still unconnected to the operator's connecting equipment, the operation of the timing means is again modified to still further prolong the 75 time interval before the busy guard is removed from the operator's position.

Further features of the invention will sufficiently appear from the specification and drawings in which Figures 1 and 1^a when 80 placed side by side diagrammatically illustrate the complete system.

Referring to Fig. 1, 3 represents a telephone line terminating in a group of first line finders, one of which is indicated at 4, 85 and having associated therewith the usual line relay 5, energized upon the initiation of a call to place selectable potential in the usual manner upon the test terminal 6 of such line where it appears in the first line 90 finder 4, and energizing the pilot or starting relay 7 common to the group of lines in which such line appears. The energization of the relay 7 closes a circuit for the power magnets 8 of all of the first line finders of 95 the group indicated which are idle, that is, of which the relays 9 and 10 are deenergized. All of such idle first line finders thereupon start in motion to select and seize the calling line in the usual manner. Immediately that 100 the brush 11 of one of such line finders makes contact with the terminal 6, the relay 12 is energized placing a busy guard upon such terminal 6 by the closure of the circuit to ground through the low resistance right-hand winding of such relay 12 and when the interrupter 13 of such line finder is opened as the brushes of such line finder are centered upon the terminals of the calling line, the shunt through such interrupter around 110

the relay 9 is removed and such relay energizing, the circuit of the power magnet 8 is opened and the circuit of the holding magnet 14 of such line finder is closed and the 5 line finder brought positively to a stop with its brushes in contact with the terminals of the calling line. The energization of the relay 9 has closed a circuit in series with the circuit for the holding magnet 14 for 10 starting a pilot relay 15 common to the group of trunk lines terminating in a given set of second line finders 16.

Assuming that the operator to whose position the connecting circuit 17 is individual 15 is idle, a circuit will be established by the energization of such relay 15 over the sequence switch contact 72, sequence switch contact 62 to the relays 18 of all such as are idle of said connecting circuits whose 20 second line finders 16 of such operator's position have access to the first line finder taken for use.

Before proceeding further it will be noted that all of the sequence switch contacts 25 shown in the upper part of Fig. 1 form a part of and are operated by the sequence switch 60 shown to the right of Fig. 1. Those sequence switch contacts shown within the dotted area in which the sequence 30 switch 70 is shown form a part of and are operated by such sequence switch. Similarly, those sequence switch contacts shown within the area delimited by the dotted line in which the sequence switch 80 is shown 35 form a part of and are operated by such sequence switch, and those shown within the area in which the sequence switch 90 is shown form a part of and are operated by such sequence switch. These switches are 40 of well-known construction and their mode of operation being known will not be described in detail herein.

Upon the energization of the relay 18 a 45 circuit is closed over its armature and front contact, armature and back contact of the relay 19, sequence switch contact 63, to the power magnet 20 of the second line finder 16 to which the connecting circuit 17 is connected. Such second line finder thereupon 50 starts in motion searching for the selectable potential which has been placed upon the test terminal 21 of the trunk 22, extending from the first line finder 4 by the energization of the relay 9 in the usual manner. As 55 soon as the test brush 23 reaches the terminal 21, a circuit is completed over the sequence switch contact 65, right-hand winding of the relay 24, sequence switch contact 82 to energize such relay 24 which thereupon 60 places the usual busy guard upon the terminal 21 by the closure of the low resistance circuit through its left-hand winding. As soon as the brushes of the line finder 16 are centered upon the terminals 65 of the trunk 22 the shunt circuit around the

relay 19 is opened by the interrupter 25, and such relay 19 is energized, opening the circuit of the power magnet 20 and closing in the usual manner the circuit of the holding magnet 20' of the line finder 16 to stop such 70 line finder in the usual manner with its brushes properly centered upon the terminals of the trunk 22.

The energization of the relay 19 also closed circuits to energize the relay 26 and 75 the power magnet of the sequence switch 60. Sequence switch 60 is driven from its first or normal position and under the influence of the local sequence switch contact 61 moves into its fourth position. The energization of the relay 26, which is maintained until the sequence switch 60 has moved out of its second position, closes a circuit over its armature and front contact and the sequence switch contact 83 to energize the power magnet of the sequence switch 80, which, together with the sequence switches 70 and 90 and the relays 27 and 28, are common to the position of the operator on which the connecting circuit 17 90 appears. The power magnet of the sequence switch 80 being energized in its first or normal position, such sequence switch moves under the control of its local contact 81 into its fourth position. The movement 95 of the sequence switch 80 out of its first position opens the sequence switch contact 82 and the sequence switch contact 83 top. On coming into its second position the circuit was closed over the sequence switch contact 84 and the sequence switch contact 73 to drive the sequence switch 70 out of its first and, under the control of its local contact 71, into its twelfth position. When the sequence switch 80 comes into its fourth position a circuit is closed over the sequence switch contact 85 and the sequence switch contact 92 top to start the sequence switch 90 in motion, which, since its local contact 100 is only open in its first or normal position, will immediately make a complete revolution. As such sequence switch 90 passes through its eighteenth position, just before returning to its first or normal position, the sequence switch contact 92 bottom is closed 110 and a circuit extends from the sequence switch contact 85, over sequence switch contact 92 bottom, to drive the sequence switch 80 into its fifth position.

When the sequence switch 60 moved into 120 its fourth position circuits were established over the sequence switch contacts 66, 67 and 68 for selecting and seizing an idle registering and controlling equipment of such operator, such selection taking place over the 125 switch 29 diagrammatically indicated, in substantially the same manner as disclosed in Patent No. 1,167,646 to F. R. McBerty.

Since it has been assumed that this operator is idle such registering and controlling 130

equipment has been found and seized before the sequence switch 80 reached its fifth position after the complete revolution of the sequence switch 90 and the sequence switch 5 60 has, therefore, been driven out of its fifth position in the known manner opening the sequence switch contact 66 included in the circuit of the switch 29 and consequently de-energizing the relays 27 and 28 in series therewith. A circuit, therefore exists when 10 the sequence switch 80 comes into its fifth position over the sequence switch contact 86 top and back contact of the relay 28 to drive the sequence switch 80 into its eighth position. In this position again a circuit is 15 closed to drive the sequence switch 80 into its tenth position, this circuit including the sequence switch contact 86 bottom and the back contact of the relay 27. On coming 20 into its tenth position, the sequence switch 80 closes the sequence switch contact 85 which again starts the sequence switch 90 to make a complete revolution. As sequence switch 90 is again passing its eighteenth position a circuit is closed over sequence switch contact 85 and 92 bottom to drive the sequence switch 80 into its eleventh position. The sequence switch 90, therefore, when it reaches its first or normal position, finds 25 the circuit connection closed over the sequence switch contacts 85 and 92 top and starts on a third complete revolution. Near the completion of the third revolution of the sequence switch 90 the closure of the sequence switch contact 92 bottom again causes 30 the energization of the power magnet of the sequence switch 80 which drives this sequence switch out of its eleventh position and passing through its twelfth, thirteenth, 35 etc., positions, such sequence switch returns to its first or normal position.

It will be observed that immediately upon the seizure of the trunk 22 whereby a call is extended to the operator's position, the apparatus of which is shown, and the consequent energization of the relays 19 and 26, 40 the sequence switch 80 started in motion and immediately drove the sequence switch 70 out of its first or normal position. This 45 caused the opening of the sequence switch contacts 72, 72', and 72^x which will be maintained open until the sequence switch 70 returns to its first or normal position. These 50 sequence switch contacts as has been before noted are included in the common starting circuits of several groups of the connecting circuits located upon the position of the operator in question. So long, therefore, as such sequence switch contacts remain open, 55 no calls may be extended to such operator's position and none of the second line finders individual to the connecting circuits appearing upon such operator's position may be set 60 in motion. When, however, the time interval necessary for the operation of the se- 65 quence switch 80 into its thirteenth position, which time interval includes definitely the time required for the sequence switch 90 to make three complete revolutions, has elapsed, the sequence switch 70 will be driven out of 70 its twelfth position by the closure of the sequence switch contact 84 bottom and such sequence switch 70 will leave its twelfth position and then, without stopping, move into its first or normal position in which the 75 sequence switch contacts 72, 72' and 72^x are closed. At this time, further incoming calls which have been extended to trunks such as 22 accessible to the set of second line finders connected to connecting circuits such as 17 80 which appear upon this operator's position, will cause the operation of such second line finders 16 in the manner hereinbefore described to extend such incoming call to a connecting circuit upon such operator's position. It will, therefore, be seen that when one call has been extended to the operator's position such operator's position is maintained busy to all further incoming calls 85 until after the passage of a definite interval 90 of time as predetermined by the adjustment, arrangement and construction of the sequence switches 70, 80 and 90. After such interval of time has passed the busy guard is removed from such operator's position 95 and a second call may be extended thereto. When the second call has been extended to a connecting circuit of such operator's position, as has been described, and in consequence thereof energized the relays 19 and 100 26 individual to the connecting circuit and second line finder to which such call has been extended, the timing apparatus is again started in motion opening the sequence switch contacts 72, 72' and 72^x and placing 105 a busy guard upon the position and maintaining such busy guard for the predetermined interval of time, after which they are again closed and a still further call may be extended to such operator's position. 110

It will be recalled that when the sequence switch 80 came into its fifth position it was assumed that the connecting circuit 17 had been connected to the operator's telephone and had associated therewith a registering 115 and controlling equipment by the switch 29 individual to such connecting circuit in the well-known manner. This was assumed for the reason that since the switch 29 and the sequence switch 90 are generally of similar 120 construction, the sequence switch 90 having made a complete revolution, the switch 29 had in the same time found and seized an idle registering and controlling equipment, since it had been assumed that the operator 125 to which such registering and controlling equipments are individual was idle.

Assuming now that for some reason the operator is delayed in attending to her duties relating to a call extended to her position 130

tion and that when the subsequent call reaches her position the switch 29 continues in operation hunting for an idle registering and controlling equipment and the operator's telephone equipment, which in the usual manner would be associated therewith if the operator was idle, the relays 27 and 28 are so adjusted that when a single switch 29 is connected in series therewith, the relay 27 alone will be energized. Therefore, although the sequence switch 80 will pass through its positions 5, 6 and 7, the relay 28 being deenergized, when it comes into position 8 no circuit is established for its own motor magnet but a circuit is established for the sequence switch 90 over sequence switch contact 86 bottom, armature and front contact of the relay 27, and sequence switch contact 92 top. This causes the sequence switch 90 to make a complete rotation and in passing through its position eighteen drives the sequence switch 80 into its ninth position over the circuit including sequence switch contact 86 bottom, front contact and armature of the relay 27, and sequence switch contact 92 bottom. At this time, if the previous call has been connected to an idle registering and controlling equipment, relay 27 will be deenergized and the timing apparatus will again operate in the usual manner. On the other hand, if such is not the case, the sequence switch 90 will start on another complete rotation over the circuit previously traced, including the front contact and armature of the relay 27 and in passing through its eighteenth position will drive the sequence 80 into its tenth position. From position 10 of the sequence switch 80 the normal operation of the timing apparatus is resumed and when, as before, the sequence switch 80 has been moved out of its twelfth position, the sequence switch 70 will be restored to normal to remove the busy guard from this operator's position. It will be observed that in the case just described, the normal period measured by the timing apparatus has been extended by the time occupied by one or two revolutions of the sequence switch 90, as may be required under the particular circumstances which exist at this operator's position.

If, even after the prolonged interval, for which the operator's position is maintained busy, just described, a further call should be extended to such operator's position, and at that time there should exist two calls, neither of which have as yet been extended to an idle registering and controlling equipment, two switches such as 29 will be connected in parallel in series with the relays 27 and 28. In this case the operation as previously described of the timing apparatus will take place in positions 1 to 4 of the sequence switch 80, but since relay 28 is now energized as well as relay 29, the sequence

switch 80 will stop in its fifth position and the sequence switch 90 will be caused to make a complete revolution while such sequence switch 80 is in its fifth position by the circuit including the sequence switch 70 contact 86 top and the armature and front contact of the relay 28. On the completion of this revolution of the sequence switch 90, the sequence switch 80 will be driven into its sixth position where it will cause a further complete revolution of the sequence switch 90 as it comes into its first position by the establishment of the same circuit. When the sequence switch 90 is again passing through its eighteenth position, the sequence switch 80 will be driven out of its sixth position into its seventh position, in which position a further revolution of sequence switch 90 takes place, after which the sequence switch 80 comes into its eighth position when the control passes to the relay 27 and the further operation of the timing apparatus takes place as has been described.

It was assumed that when the sequence switch 80 came into its sixth and seventh positions there were still two switches 29 hunting for an idle registering and controlling equipment, and therefore connected in the same circuit with the relays 27 and 28, causing the relay 28 to be energized. Therefore, the time for two further additional revolutions was inserted in the predetermined interval for which the operator's position was maintained busy under the circumstances set forth. If at this time, however, on the contrary one of these switches 29 had connected the call associated therewith to an idle registering and controlling equipment, the relay 28 would have fallen off and the sequence switch 80 would have passed directly into its eighth position, and one or two of the revolutions of the sequence switch 90 would have been eliminated.

It will, therefore, be seen that if two calls have been extended to an operator's position, neither of which have as yet reached the operator, the operator's position will not only be maintained busy for the normal period plus the period required for the two revolutions of the sequence switch 80 caused by the energization of the relay 27, but will be maintained busy for the further period required by the one, two or three revolutions of the sequence switch 90, as the case may be, due to the energization of the relay 28 in the fourth, fifth and sixth, or fifth, sixth and seventh positions of the sequence switch 80.

In résumé it will be seen that under normal conditions upon the receipt of a call, the operator's position will be maintained busy for a period say of four seconds, after which time another call may be extended to her position. If, however, a call has been extended to her position which has not as yet been connected to her equipment, the test guard

will be maintained upon the position an increased interval which may even be as much as seven seconds, and if two calls have been connected to such operator's position, neither 5 of which have as yet been extended to her equipment, the interval may be further extended to so much, for example, as eleven seconds.

It will, of course, be understood that the 10 time intervals referred to are given for example only and that by the rearrangement of the circuits in an obvious manner, the period of time elapsing in the normal operation of the timing apparatus or in either 15 of the abnormal cases mentioned may be so modified as the traffic conditions of the particular exchange in which the apparatus is used may require. Generally, it will probably be found that if the time occupied by 20 the timing apparatus in its normal operation is about seventy-five per cent of the time normally required by an operator to complete her duties with regard to the average call, a considerable saving will be accomplished with a minimum delay to incoming 25 calls.

What is claimed is:

1. In a call distributing system, means for selecting an operator's position and extending a call thereto, means at such position for establishing connections between calling and called lines, and means independent of such connecting means for rendering the position busy to subsequent calls for a normal predetermined time interval after the distribution of a call thereto, and means dependent upon the condition of such connecting means for rendering the position busy for a further predetermined interval.
2. In a call distributing system, means for distributing calls to an operator's position in combination with timing means at said position for automatically determining the normal rate at which such calls may be distributed to such position, and means dependent upon the condition of such connecting apparatus for automatically altering such rate of distribution.
3. In a call distributing system, means for distributing calls to an operator's position, means for associating such distributed calls with connecting circuits at such position, controlling apparatus adapted to be associated with such connecting circuits, a timing device at such position adapted to introduce a time interval between the distribution of successive calls of the connecting circuits at such position, and means controlled

by the operative condition of the controlling devices associated with the connecting circuits at the position for modifying the operation of such timing device.

4. In a call distributing system, means for distributing calls to an operator's position, means for associating such distributed calls with connecting circuits at such position, automatic means for selecting and associating a controlling equipment with connecting circuits to which calls have been distributed, means at said position for introducing a time interval between the distribution of successively calls to such connecting circuit, and means controlled by the number of controlling equipments which are simultaneously in operation for determining the extent of such time interval.

5. In a call distributing system, an operator's position, connecting circuits at such position, calling lines, means for selecting such position and extending such calling lines to such connecting circuits, a plurality of controlling equipments, automatic switches for selecting and connecting such controlling equipments to connecting circuits taken for use, means for maintaining such position non-selectable to calling lines for a definite time interval after the extension of a calling line to a connecting circuit, and means dependent upon the number of automatic switches simultaneously operating to select controlling equipments to determine the extent of such time interval.

6. In a call distributing system, an operator's position, connecting circuits at such position, calling lines, means for selecting such position and extending such calling lines to such connecting circuits, controlling equipments adapted to be associated with such connecting circuits, equipment selector switches adapted to select idle controlling equipments and associate them with connecting circuits to which calling lines have been extended, a sequence switch adapted to be moved from normal each time a calling line is extended to a connecting circuit at the position to render the position non-selectable to calling lines, a timing device for returning such sequence switch to normal to render the position selectable after a time interval, and marginal relays included in the operating circuit of the equipment selector switches for determining the duration of said time interval.

In witness whereof, I hereunto subscribe my name this 2nd day of March A. D., 1917.

LIPA POLINKOWSKY.
